(57) **CLAIM**

The ornamental design for a game disk case, as shown and described.

DESCRIPTION

FIG. 1 is a front, top and right perspective view of a first embodiment of a game disk case showing our new design, the case being opened, a dotted line showing portions other than the new design;

FIG. 2 is a rear, bottom and left perspective view of the first embodiment, the case being opened, a dotted line showing portions other than the new design;

FIG. 3 is a front, top and right perspective view of the first embodiment, a disk holder is detached from the case, the case being opened, a dotted line showing portions other than the new design;

FIG. 4 is a rear, bottom and left perspective view of the first embodiment, the disk holder being detached from the case, the case being opened, a dotted line showing portions other than the new design;

FIG. 5 is a top plan view of the first embodiment, the case being opened, a dotted line showing portions other than the new design;

FIG. 6 is a bottom view of the first embodiment, the case being opened, a dotted line showing portions other than the new design;

FIG. 7 is a front view of the first embodiment, the case being opened, a dotted line showing portions other than the new design;

FIG. 8 is a rear view of the first embodiment, the case being opened, a dotted line showing portions other than the new design;

FIG. 9 is a right side view of the first embodiment, the case being opened, a dotted line showing the new design;

FIG. 10 is a left side view of the first embodiment, the case being opened, a dotted line showing the new design;

FIG. 11 is a front, top and right perspective view of the first embodiment, the case being closed, a dotted line showing portions other than the new design;

FIG. 12 is a top plan view of the first embodiment, the case being closed, a dotted line showing portions other than the new design;

FIG. 13 is a bottom view of the first embodiment, the case being closed, a dotted line showing portions other than the new design;

FIG. 14 is a front view of the first embodiment, the case being closed, a dotted line showing portions other than the new design, a rear view being a mirror image;

FIG. 15 is a right side view of the first embodiment, the case being closed, a dotted line showing portions other than the new design; and,

FIG. 16 is a left side view of the first embodiment, the case being closed, a dotted line showing portions other than the new design.

The broken lines showing the surrounding case throughout the views, illustrate the portions of the design that form no part of the claim.
